UNITED STATES PATENT OFFICE.

KATHARINE L. STANDISH, OF NEW YORK, N. Y.

DESIGN FOR A HAND TELEPHONE-RECEIVER SUPPORT.

49,679.

Specification for Design.

Patented Sept. 19, 1916.

Application filed June 24, 1916. Serial No. 105,762. Term of patent 14 years.

To all whom it may concern:

Be it known that I, KATHARINE L. STANDISH, a citizen of the United States, residing at New York, in the county of New York and State of New York, have invented a new, original, and ornamental Design for Hand Telephone-Receiver Supports, of which the following is a specification, reference being had to the accompanying drawing, forming part thereof.

The figure is a perspective view of a hand telephone-receiver support, showing my new design.

I claim—

The ornamental design for a hand telephone-receiver support, as shown.

KATHARINE L. STANDISH.
